UNITED STATES PATENT OFFICE.

EUGENE BALLOU, OF TOLEDO, OHIO.

ROTARY VALVE.

1,018,386.

Specification of Letters Patent. Patented Feb. 20, 1912.

Application filed November 7, 1910. Serial No. 590,978.

To all whom it may concern:

Be it known that I, EUGENE BALLOU, a citizen of the United States, residing at Toledo, Lucas county, Ohio, have invented a new and useful Rotary Valve, of which the following is a specification.

This invention relates to a motor, and more particularly to a valve and the packing for said valve.

10 This invention has utility when adapted to internal combustion motors.

Referring to the drawings: Figure 1 is an elevation with parts broken away showing an embodiment of the invention in an internal combustion engine; Fig. 2 is a section of the device at right angles to the showing in Fig. 1; and Fig. 3 is a detail view on an enlarged scale of the rotary valve element, one-half being in section.

20 The motor cylinder 1 is shown as provided with the reciprocable piston 2 having connecting rod 3 and crank shaft 4. The crank or drive shaft 4 has fixedly mounted thereon the sprocket wheel 5 to drive 25 through the noiseless sprocket chain 6 the sprocket wheel 7 on the valve shaft 8 at one-quarter the speed of the shaft 4. This shaft 8 may have formed thereon a spherical portion 9, one for each of the cylinders 30 in the group of motors comprising the motor structure. The sphere 9 is provided with a diametrical port 10 perpendicular to the shaft 8. Packing rings 11 of zone form are arranged on the surface of the valve laterally of port 10, the planes of the rings being parallel to the axis of the shaft 8 and to the axis of said port. Two of these packing rings 11 are shown on each side of the port 10. These expansion packing rings 11 each have a step take up joint 12. Housing 13 for the spherical valve member 9 has intake or fuel supply port 14 and exhaust port 15 as to which the valve port 10 may move in and out of registry in its travel in 45 and out of registry as to cylinder port 16. To ignite the charge of fuel in the cylinder, the spark plug 17 may be used. Lubricant ducts 18 for the valve shaft 8 supply ample lubricant for the ported spherical valve member 9 as well as its packing rings 11. This spherical valve 9 may more or less 50 nearly approximate a close running fit in

the ported head of cylinder 1 and the ported cap 13.

In operation, the four to one speed reduction allows of such a materially slower travel for the valve as to make possible close bearings for the shaft 8. This valve is shown in position in Fig. 2 of just completing the intake of fuel and about to move 60 toward compression. The elements at the right in Fig. 1 show the piston in compression position and the valve 9 with its four rings 11 efficiently packing the port 16 as to the ports 14 and 15. At such stage ignition of the charge may occur. As the piston 2 reaches the limit of its down stroke the port 16 is in communication with the port 15 by means of the port 10 so that exhaust may occur as the piston 2 has its upward 70 scavenging stroke. The continued travel of the valve 9 brings the port 10 into registry with the fuel supply port 14 to have the fuel drawn in through port 16 as the piston 2 returns from its scavenging stroke. 75 This intake of fuel following the discharge of exhaust has a warming effect upon the fuel in its passage through the hot valve 9, which giving of heat to the fuel where it is desired serves to cool the valve 9. With 80 this charge warmed by the valve 9 in the cylinder 1, the piston 2 starts on its compression stroke and when compressing the packing rings 11 are in position to hold the charge during the firing after which the 85 valve 9 so rotates that travel through its port 10 to exhaust through port 15 may occur. By this four to one operation the valve port 10 has exhaust in one direction of the port at one scavenge, and an opposite 90 direction through the same port at the next scavenge due to the fact that the port 10 is turned end for end between its compressions.

In providing packing rings, expansion is 95 readily taken care of to insure a holding of pressure and elimination of any binding. The disposal of the packing rings in a plane parallel to the axis of rotation places these rings in their travel transversely of the relative movement between the surfaces packed and accordingly insures a movement against binding. The double packing is of exceptional value in insuring a structure which

will not leak during the high pressure of expansion. The absence of reciprocating parts in the valve control results in producing a noiseless motor of exceeding simplicity.

The cylinder and cylinder head may be cooled as found desirable.

What is claimed and it is desired to secure by Letters Patent is:

- 10 1. In an internal combustion engine the combination with a part having a valve seat, of a valve fitting within said seat, such valve comprising a shaft and a valve member of double curvature carried thereby, such valve member having a port extending centrally therethrough at right angles to the axis of said shaft, said seat having oppositely disposed ports adapted to coöperate with the port in said valve member, and 20 packing rings carried by said valve member on each side of said centrally extending port, said rings lying in planes parallel with said port and with the axis of the shaft.
2. In an internal combustion engine, the combination with a part having a valve seat, 25 of a valve fitting within said seat, such valve comprising a shaft and a valve member of double curvature carried thereby, said valve member having a port extending centrally therethrough at right angles to 30 said shaft, said seat having oppositely disposed ports coöperating with the port in said valve member, and packing rings carried by said valve member on each side of said centrally extending port, all parts of 35 each of said rings lying in a true plane, whereby the effects of expansion are rendered uniform throughout the periphery of the ring.

In testimony whereof I affix my signature 40 in the presence of two witnesses.

EUGENE BALLOU.
